(57) **CLAIM**

The ornamental design for a portion of a display assembly, as shown and described.

DESCRIPTION

FIG. 1 is a perspective view of a portion of a display assembly showing our new Design in accordance with a first variant of said Design, in which containers of the display assembly are shown in a resting position;

FIG. 2 is a front view of the portion of a display assembly shown in FIG. 1;

FIG. 3 is a right-side view of the portion of a display assembly shown in FIG. 1;

FIG. 4 is a left-side view of the portion of a display assembly shown in FIG. 1;

FIG. 5 is a rear view of the portion of a display assembly shown in FIG. 1;

FIG. 6 is a top plan view of the portion of a display assembly shown in FIG. 1;

FIG. 7 is a bottom plan view of the portion of a display assembly shown in FIG. 1; and,

FIG. 8 is a further perspective view of the portion of a display assembly shown in FIG. 1, in which a container of the display assembly is shown in an extended position.

The broken lines depict portions of the article that form no part of the claimed design. All surfaces not shown form no part of the claimed design. The shade lines in the Figures show contour and not surface ornamentation. The oblique line shading in the Figures shows a transparent surface and not surface ornamentation.

1 Claim, 8 Drawing Sheets
